US00D624515S

(12) **United States Design Patent**
Kim et al.

(10) **Patent No.:** US D624,515 S
(45) **Date of Patent:** ** Sep. 28, 2010

(54) **MOBILE PHONE**

(75) Inventors: **Sung-Kwon Kim**, Gwangmyeong-si (KR); **Seung-Min Park**, Seoul (KR); **Seog-Guen Kim**, Seoul (KR)

(73) Assignee: **Samsung Electronics Co., Ltd.**, Suwon-Si (KR)

(**) Term: **14 Years**

(21) Appl. No.: **29/332,130**

(22) Filed: **Feb. 10, 2009**

(30) **Foreign Application Priority Data**

Nov. 21, 2008 (KR) 30-2008-0050284

(51) **LOC (9) Cl.** 14-03

(52) **U.S. Cl.** D14/138 AB

(58) **Field of Classification Search** D14/138 AB, D14/138 R, 138 AD, 138 G, 341-347, 203.4, D14/203.7, 203.2, 191; 455/575.3, 575.1, 455/556.2; 379/433.11, 433.13; D21/517

See application file for complete search history.
